UNITED STATES PATENT OFFICE.

JOHN T. REMEY, OF NEW YORK, N. Y.

METHOD AND APPARATUS FOR FORMING LETTERS AND SYMBOLS IN THE AIR.

Application filed December 7, 1923, Serial No. 679,239. Renewed May 2, 1929.

This invention is a method and apparatus for forming letters or symbols in the air by means of smoke or vapor trails, which may be called "sky typing."

5 The letter or symbol is built up from a plurality of smoke trails, which are substantially parallel and generally contiguous. These smoke trails are formed from a plurality of smoke-emitting units which have 10 relative movement with respect to the air. These smoke-emitting units may be actually moved through the air horizontally or vertically, or may be fixed in a vertical or horizontal position in a moving body of 15 air.

The invention, as above expressed, may be carried out in a number of different ways. The preferred way of carrying it out is to suspend a control column, having a large 20 number of smoke-emitting valves at spaced intervals therealong, from a moving aircraft, and to open selectively the different valves so that they will form smoke trails of a controlled length at controlled intervals.

25 In this preferred embodiment of the invention, the control column is flexible so that it may be reeled up in the aircraft, and is hollow for carrying smoke or a smoke producing compound to the valves that it carries.

The column also carries elements, such as wires, leading to the valves for controlling them. It is provided with a weight at its lower end for holding it substantially vertical. The valves are opened and closed selectively and individually, in any desired manner; the preferred control is electromagnetic, each valve having its own electromagnet. These magnets are in turn 35 controlled by a power driven perforated strip, as will be described in detail below.

Each valve has its own control, so that it may be opened at any point, kept open as long as desired, and closed at any point. 45 An intermittent smoke trail may be produced by successively opening and closing the valve. The length and placement of each smoke trail may be readily controlled in this manner.

50 The term "smoke" as herein used, is not to be limited to products of combustion, but is of broader meaning, and is intended to cover any desired form of "smoke" or vapor, a fluid or fluids or compounds for forming 55 "smoke" or vapor that is visible in the day-

time or night time. The invention is in the method and in the apparatus, and not in any particular kind of smoke. The preferred "smoke" is made from titanium tetrachloride; this is a liquid which has a strong 60 affinity for moisture. It fumes in ordinary air, and when sprayed into the air forms a dense cloud of white vapor or "smoke" by reacting with the moisture in the air; this vapor persists with a fairly high degree 65 of permanency. At night, luminous vapor or sparks might be used.

The control column may be suspended from a moving aircraft; it may extend upwardly, by means of a small balloon, or 70 downwardly, by means of a weight. It may be positioned vertically, as on a tall building, being operated when there is a breeze to carry away the smoke trails. It may be positioned horizontally, being operated when 75 there is a breeze to carry away the trails and to form letters or symbols in a horizontal plane, readily visible from the air.

In another aspect of the invention, the contiguous smoke trails may be formed by 80 dropping in rapid succession small smoke-producing "bombs" from a moving aircraft, each bomb being designed to trace a smoke trail of any desired length at any point in its fall. These bombs are preferably suspended in series along a fuse, which, as it burns, releases the bombs and lights them. Each of these "bombs" carries one or more smoke-producing segments with a fuse extending through each segment. The position of each segment on this fuse determines at what point it starts to produce smoke; the length of each segment determines the time it will produce smoke, that is to say, determines the length of the smoke 95 trail this bomb will produce during its fall.

The broader features of the invention having been outlined, the preferred apparatus for carrying it out will now be described. It should be understood that the structural 100 details here described are only illustrative of the invention, and that it may be carried out in other ways than in the precise form shown in the accompanying drawings.

In these drawings, 105 Fig. 1 shows, more or less diagrammatically, a side view of a preferred form of apparatus for sky typing;

Fig. 2 is a side view of a part of the control column, on a larger scale; 110

- Fig. 3 is a side view, partly in section, of the control column, on a still larger scale; Figs. 4, 5, 6 and 7 are sections taken on lines 4—4, 5—5, 6—6, and 7—7 of Fig. 3; 5 Fig. 8 is a diagrammatic side view of winding and control mechanism at the upper end of the control column; Fig. 9 is a view of a reel in which the control column is wound; 10 Fig. 10 is a detail of the control mechanism; Fig. 11 shows part of a multi-wire coupling; 15 Fig. 12 is a diagrammatic view showing the circuit for controlling the valves; Fig. 13 is a view of the perforated control strip, perforated so that the letter A will be printed by the smoke trails; 20 Figs. 14 and 15 illustrate different placements for the control column; Fig. 16 illustrates a modified method of carrying out the invention; 25 Fig. 17 is a smoke bomb holder for use in this modified method; Fig. 18 is an end view of Fig. 17; Fig. 19 is a detail of a smoke bomb. Referring now to these drawings, in which similar reference characters indicate similar parts, the control column, indicated at 5, is 30 provided with a plurality of smoke-emitting valves 6 spaced at short intervals along it. The control column may be moved through the air, or may be more or less stationary, and placed in a moving body of air. In 35 either case, there is relative movement between the control column and the air, and preferably the column extends transversely to the direction of such relative movement. In Fig. 1, the control column is suspended 40 from a moving aircraft 7, a weight 8, streamlined, being carried at the lower end thereby so as to hang nearly vertical. The aircraft 7, if lighter than the air, could be anchored, or held stationary by its engine, and the 45 smoke trails formed when there is a breeze. The smoke-emitting valves 6 are preferably well below the aircraft so as to be out of the propeller wash. The number and spacing of such valves is optional, dependent 50 upon the desired size and definition of the letter to be formed or "typed." Each of the smoke-emitting valves 6 is supplied with "smoke" or a smoke producing compound, and each is individually operated, so that the length and placement of each smoke trail may be controlled. In Fig. 55 1, the upper and lower valves 6 have traced continuous smoke trails 6', and the intermediate valves have traced intermittent smoke trails 6'', the placement and length of the trails being such as to form the letter "O". The control column 5 comprises a stranded cable 10 of bronze or steel wires, as its main 60 supporting element. The control column 65 carries the smoke-emitting valves, carries smoke to each valve, and carries the electric wires leading to each valve. Referring particularly to Figs. 3—7, the valve housing for each of the smoke-emitting valves 6, is indicated at 12. A tube 13 is brazed to one side of the valve housing, the upper and lower ends of the housing extending above and below it. Lengths of rubber hose 14 connect the upper end of a tube 13, with the lower 70 end of the tube 13 next above it; the hose being firmly secured to the tubes 13 by clamps 15. A continuous channel is thus formed for the passage of smoke or smoke producing fluid along the control column. 75 The control column also carries a plurality of electric wires 16, suitably insulated, one wire for each of the valves 6. A wrapping tape 17 binds the cable 10, hose 14 and wires 16 together, giving a smooth external contour, thus lessening the wind resistance. 80 The smoke-emitting valves may be constructed in a number of different ways. In the preferred construction, the valve housing 12 is bored centrally for receiving the 85 valve stem 20, which is movable up and down and is provided with a transverse smoke passage 21. The smoke passage 21 extends through the housing and into the tube 13 on one side, and through the housing and 90 through a nozzle element 22, set into the housing, on the other side. 95 The lower end of the valve stem 20 is provided with a key 23 parallel with the smoke passage 21, which key moves up and down 100 with the stem, in a slot 24 cut into a plug 25 held in the housing 12 by a set screw 26, the slot being parallel to the smoke passage 21. When the upper surface of the key 23 is 105 against the housing 12, as shown in Fig. 3, the smoke passage of the stem registers with the other smoke passages, and smoke is emitted. The valve stem is pressed down by a spring 27 bearing against a cap 28 carried by the top of the housing so that the valve 110 is normally held closed by the spring. 115 The valves are preferably magnetically operated. The stem 20 is of iron or steel, and acts as the core for the solenoid 30. Of the two wires for leading current through the solenoid, one, indicated at 31, is connected to one of the wires 16, while the other is "grounded" through cable 10. The wires 31 and 32 leave the solenoid through a hollow plug 33 screwed into cap 28. A separate 120 wire 16 is provided for each solenoid, so that it may be individually controlled. It will be apparent that as long as the solenoid is energized, the valve will be open, and will emit smoke. The spring 27 closes the 125 valve as soon as the circuit is broken. The length of each smoke trail is then accurately controlled. 130 The hollow and flexible control column is stored in the aircraft when not in use. For

example, it may be wound on a reel 40, suitably mounted on standards 41 in the body of the aircraft. Pawl and ratchet mechanism 42 and 43 is provided for latching the reel in any desired position. Manual or other power means, such as handle 44, may be provided for raising and lowering the control column. The reel 40 is provided in its surface with a spiral groove 45, in which the control column 10 fits as it is wound thereon, the valves, when the column is so wound, facing outwardly.

Means are provided for coupling the longitudinal smoke passage of the control column to a smoke supply, and for coupling the 15 several wires 16 to their respective controlling devices.

To this end, the control column 5, at its upper end, is provided with a hollow branch 50 terminating in a coupling element 51, 20 which is adapted to couple to a cooperating element 52, to which is attached a tube 53, connected through a two-way valve 54 to a pipe 55 the ends of which lead into the top and bottom of a pressure tank 56 for holding 25 the titanium tetrachloride or other smoke or smoke-producing fluid or compound. A body of dry air under pressure is maintained in the tank 56 such air having passed through an air dryer 57 of any desired type, 30 and a pump 58, which may be manually or power operated. The connecting pipes 59 may be provided with check valves 60.

The coupling elements 66 and 67 are unsymmetrical about one axis, as shown in Fig. 35 11, so that it is possible to couple up the wires in only the correct way.

Control mechanism for selectively opening and closing the smoke valve 6 at any desired point, will now be described. While this 40 control may take other forms, a preferred type will be described.

The control column at its upper end, is also provided with a second branch 65 which is connected to a multi-wire connector of 45 any suitable type, one plate 66 of which is indicated in Fig. 11. The connector 66 is provided with a plurality of sockets 67, and to each socket is connected one of the wires 16 of the control column. The other plate 50 68 of the multi-wire connector is provided with a corresponding plurality of plugs, not shown, for plugging into respective sockets 67. To each plug is connected a wire 16', see Fig. 12, which in turn is connected to a brush 55 70, one for each wire 16 and 16'. The brushes are mounted in an insulated arm 71. The brushes 70 are adapted to bear against a conducting bar 72 which is connected to one terminal of a battery 73, the other terminal 60 being connected to the supporting cable 10. 74 is a switch.

It is evident from Fig. 12 that an impulse sent through one of the brushes to one of the valves will open that valve and hold it open 65 as long as the circuit is maintained.

The opening and closing of the respective circuits, and therefore of the respective smoke-emitting valves, is controlled by a movable strip, suitably perforated, made of non-conducting material. The perforated 70 strip indicated at 75, Fig. 8, is wound on a reel 76, led over bar 72 and under the brushes 70 and attached to a power driven winding reel 77, driven by a motor 78.

The control strip 75 is provided with 75 perforations 79 corresponding with the letter or symbol it is desired to form in smoke.

It will be understood that the apparatus shown in Fig. 8 is mounted in the fuselage or nacelle of the aircraft. 80

The operation of the apparatus thus far described is as follows:—The control column 5 is lowered from the aircraft by unwinding it from reel 40. The smoke and electric couplings are coupled together, as in Fig. 8. 85 All moist air is blown out of the control column and valves by connecting the top of tank 56, through valve 54, to blow dry air through the system. Then valve 54 is turned to fill the system with smoke, valves 90 6 being opened in any suitable way, as by closing circuits through each valve, as in Fig. 12, before the insulating strip 75, is in position. The apparatus is now ready to form the smoke trails of definite length, 95 definitely placed. The strip 75 is started, and as the perforations 79 come under fingers 70, corresponding circuits are closed, certain valves are opened, and smoke is emitted, as long as such circuit is closed. 100 As a perforation ceases, the circuit is broken, and the corresponding smoke trail ceases. The smoke trails in Fig. 1 are more or less contiguous, and parallel and form the letter "O". 105

After the operation is complete, the smoke or smoke producing compound may be cleared out of the system by manipulating valve 54 to blow dry air through the system. In Figs. 14 and 15, different placements for 110 the control column 5 are illustrated. The control column in each case is fixed, relative movement between the column and the wind existing during a breeze. Each of these control columns is provided with valves 115 6, operated as described above, and controlling mechanism as described for opening and closing them selectively and individually.

In Fig. 14, the control column is rigid, and extends vertically from a tall building, 120 and forms letters in a vertical plane.

In Fig. 15, the control column extends horizontally between standards S and forms letters in a horizontal plane. These letters are evidently readily visible from an aircraft in flight. The standards may be movable according to the direction of the wind. 125

Another way of forming the contiguous, substantially parallel smoke trails, is illustrated in Figs. 16-19 inclusive; here the smoke 130

trails are formed by smoke bombs dropped in rapid succession from a moving aircraft, each bomb being designed to form one or more smoke trails of any desired length at 5 any point in its fall.

The smoke bombs 80, about forty or fifty for each letter, have a fuse 81 extending therethrough, the upper ends of the fuses being connected to a master fuse 82, held in 10 a slotted tube 83 suitably mounted in an aircraft. Associated with tube 83 is an open ended casing 84.

Each fuse 80 is provided with one or more smoke-producing segments 85 made of any 15 desired smoke producing materials, the length of each segment being regulated according to the length of each smoke trail this bomb is expected to trace, and the placement of each segment being regulated according to the desired placement of the 20 smoke trails. The bomb of Fig. 19 will first trace two short, separated trails, and then a longer trail. Graded weights 86 may be carried by the bombs, so as to bring them to 25 approximately the same weight. The segments 85 will be designed with due regard to the acceleration of the fall of the bomb.

The operation is as follows:—The master fuse is lighted; as it burns at uniform rate, 30 it will release the bombs at a uniform rate, lighting each one as it is released. Fuse 81 in the bomb burns uniformly and traces one or more smoke trails as determined by the segments 85. In Fig. 16, the smoke 35 trails form the letter "R".

Instead of dropping the smoke bombs from a moving aircraft, they could be dropped from a holder, a casing that is moved by gravity or power along a suspended 40 wire or cable.

While I have described my method and apparatus in some detail, it should be understood that the disclosure is illustrative and not restrictive of the invention, and that 45 it may be embodied in other structural forms.

I claim as my invention:—

1. The method of forming letters or symbols with smoke, comprising the formation 50 of a plurality of contiguous, substantially parallel smoke trails.

2. The method of forming letters or symbols with smoke, comprising the intermittent formation of a plurality of contiguous 55 substantially parallel smoke trails.

3. The method of forming letters or symbols with smoke, comprising forming a plurality of contiguous smoke trails, and controlling the length of each smoke trail.

4. The method of forming letters or symbols with smoke, comprising the formation 60 of a plurality of substantially parallel smoke trails, and controlling the length of the smoke trails.

5. The method of forming letters or sym-

bols with smoke, comprising the formation of a plurality of contiguous and substantially parallel smoke trails, and controlling the length of the smoke trails.

6. The method of forming letters or symbols with smoke, comprising the formation of a plurality of substantially parallel smoke trails, and controlling the length of the smoke trails, each of the smoke trails being in the same plane as the plane of the letter 75 or symbol.

7. The method of forming letters or symbols with smoke, comprising the formation of a plurality of contiguous and substantially parallel smoke trails, and controlling 80 the lengths of the smoke trails, each of smoke trails being in the same plane as the plane of the letter or symbol.

8. The method of forming letters or symbols with smoke, comprising releasing 85 trails of smoke from a control column at a plurality of points along the column into air that is moving with respect to the control column.

9. The method of forming letters or symbols with smoke, comprising placing a control column in a body of air that has relative movement with respect to the control column, the column extending transversely with respect to the relative motion of the 95 air, releasing trails of smoke from a plurality of points along the column, and controlling the length of each trail.

10. The method of forming letters or symbols in the sky, comprising lowering a 100 control column from an aircraft, and releasing trails of smoke from a plurality of points along the control column.

11. The method of forming letters or symbols in the sky, comprising lowering a 105 control column from an aircraft, releasing trails of smoke from a plurality of points along the control column, and controlling the length of each of the trails of smoke.

12. The method of forming letters or symbols in the sky, comprising suspending a control column from a moving aircraft, releasing trails of smoke from the control column at a plurality of points therealong, and controlling the length of each of the 115 smoke trails.

13. The method of forming letters or symbols with smoke with an aircraft, comprising the formation of a plurality of smoke trails which are substantially parallel to each other and substantially parallel 120 to the direction of flight of the aircraft.

14. The method of forming letters or symbols with smoke with an aircraft, comprising the formation of a plurality of smoke trails which are substantially parallel to each other and substantially parallel 125 to the direction of flight of the aircraft, and controlling the length and relative placement of the smoke trails.

15. The method of forming letters or symbols with smoke with an aircraft, comprising the formation of a plurality of smoke trails which are substantially parallel to each other and substantially parallel to the direction of flight of the aircraft and are in the same plane as the plane of the letter or symbol.
16. The method of forming letters or symbols with smoke with an aircraft, comprising releasing trails of smoke from a control column, at a plurality of points therewith, the column extending from the aircraft in a direction substantially perpendicular to the direction of flight of the aircraft, and controlling the length and placement of the smoke trails.
17. The method of forming letters or symbols with smoke with an aircraft, comprising releasing trails of smoke from a plurality of points along a control column which extends from the aircraft in a direction substantially perpendicular to the direction of flight thereof, and controlling the length and placement of the smoke trails, the trails of smoke extending in a direction substantially parallel to the direction of flight of the aircraft, and being positioned in the same plane as the plane of the letter or symbol.
18. An apparatus for forming letters or symbols in smoke, comprising a control column, a plurality of smoke-emitting valves carried along the column, and means for individually controlling the valves.
19. An apparatus for forming letters or symbols in smoke, comprising a control column for carrying smoke or a smoke-producing compound, a plurality of smoke-emitting valves carried along the column, and means for individually controlling the valves.
20. An apparatus for forming letters or symbols in smoke, comprising a control column for carrying smoke or a smoke-producing compound, a plurality of smoke-emitting valves arranged along the column, and electrically operated means for individually controlling the valves.
21. An apparatus for forming letters or symbols in smoke, comprising a flexible and hollow control column for carrying smoke or a smoke producing compound, a plurality of smoke emitting valves arranged along the control column, and means for individually controlling the valves.
22. An apparatus for forming letters or symbols in smoke in the sky comprising an aircraft, a control column carried thereby, a plurality of smoke-emitting valves arranged along the control column, and means for individually controlling the valves.
23. An apparatus for forming letters or symbols in smoke in the sky comprising an aircraft, a control column carried thereby, a plurality of smoke-emitting valves ar-
- ranged along the control column, and means controlled from within the aircraft, for individually operating the valves.
24. An apparatus for forming letters or symbols in smoke in the sky comprising an aircraft, a tank of smoke or smoke producing compound carried thereby, a hollow control column adapted to extend away from the aircraft and connected to the tank, a plurality of smoke emitting valves arranged along the control column, and means for individually controlling the valves.
25. An apparatus for forming letters or symbols in smoke, comprising a control column, a plurality of smoke-emitting valves carried along the column, and means including a perforated strip for individually controlling the valves.
26. An apparatus for forming letters or symbols in smoke, comprising a control column for carrying smoke or a smoke-producing compound, a plurality of smoke-emitting valves arranged along the column, and electrically operated means including a perforated strip for individually controlling the valves.
27. An apparatus for forming letters or symbols in smoke in the sky, comprising an aircraft, a control column carried thereby, a plurality of smoke-emitting valves arranged along the control column, and means including a perforated strip carried in the aircraft, for individually controlling the valves.
28. An apparatus for forming letters or symbols in smoke, comprising a hollow control column, a tank for carrying smoke or a smoke producing compound connected to the control column, a plurality of smoke-emitting valves arranged along the control column, means including a perforated strip for individually controlling the valves, and means for moving the perforated strip.
29. An apparatus for forming letters or symbols in smoke in the sky comprising an aircraft, a hollow control column adapted to extend away from the aircraft, a tank for carrying smoke or a smoke producing compound mounted in the aircraft and connected to the control column, a plurality of smoke-emitting valves carried along the control column, and means for controlling the valves, comprising a power-driven perforated strip carried in the aircraft.
30. An apparatus for forming letters or symbols in smoke in the sky comprising an aircraft, a flexible control column adapted to extend away from the aircraft, a plurality of smoke-emitting valves carried along the control column, means for individually controlling the valves, and means for reeling up the control column within the aircraft.
31. An apparatus for forming letters or symbols in smoke in the sky comprising an aircraft, a flexible, hollow control column

adapted to extend away from the aircraft, a tank in the aircraft connected to the control column, a plurality of smoke-emitting valves carried by the control column at spaced intervals therealong, means for individually controlling the valves, and means for coiling up the control column in the aircraft.

32. An apparatus for forming letters or symbols in smoke in the sky comprising an aircraft, a flexible, hollow control column adapted to extend away from the aircraft, a tank in the aircraft connected to the control column, a plurality of smoke-emitting valves carried by the control column at spaced intervals therealong, means including a power-driven perforated strip mounted in the aircraft, for individually controlling the valves, and means for coiling up the control column in the aircraft.

33. An apparatus for forming letters or symbols in smoke in the sky comprising an aircraft, a flexible control column depending therefrom, a weight at the lower end of the control column, smoke-emitting valves at spaced intervals along the control column, and means mounted in the aircraft for controlling the operation of the valves.

34. An apparatus for forming letters or symbols in smoke, comprising a flexible hollow control column for carrying smoke or a smoke-producing compound, electrically-operated valves at spaced intervals along the control column, a reel for winding up the control column, electric wires carried by the

control column, and connected to the several valves, and detachable couplings through which smoke or a smoke-producing compound, and electric impulses, are supplied to the control column.

35. An apparatus for forming letters or symbols with smoke, comprising a control column, a plurality of smoke-emitting valves carried by the column, and means carried by the column for lessening its wind resistance.

36. An apparatus for forming letters or symbols with smoke, comprising a supporting cable and a smoke-carrying conduit, smoke-emitting valves carried by the cable and operatively connected to the conduit, and means for lessening the wind resistance of the column.

37. An apparatus for forming letters or symbols with smoke, comprising a control column, a plurality of smoke-emitting valves carried thereby, means for controlling the valves, and a stream-lined weight carried by the lower end of the column for holding it down.

38. An apparatus for forming letters or symbols with smoke, comprising a control column, a plurality of smoke-emitting valves carried thereby, means for controlling the valves, means for lessening the wind resistance of the column, and a stream-lined weight carried by the lower end of the column for holding it down.

In testimony whereof I affix my signature.

JOHN T. REMEY.
